FIG. 1

FIG. 2

FIG. 3

INVENTOR

James D. Adams
By Ray F. Tamm / Brown
Acting

UNITED STATES PATENT OFFICE.

JAMES D. ADAMS, OF BELLE VERNON, PENNSYLVANIA.

FURNACE COVER OR DOOR.

1,386,218.

Specification of Letters Patent. Patented Aug. 2, 1921.

Application filed July 10, 1920. Serial No. 395,301.

To all whom it may concern:

Be it known that I, JAMES D. ADAMS, a citizen of the United States, and resident of Belle Vernon, in the county of Westmoreland and State of Pennsylvania, have invented a new and useful Improvement in Furnace Covers or Doors; and I do hereby declare the following to be a full, clear, and exact description thereof.

10 My invention relates to furnace covers or doors.

While my invention is applicable to furnace covers or doors, generally, it has particular application to soaking-pit covers employed in steel plants. Heretofore in making these soaking-pit covers, it has been customary to make a cast-iron frame and line the same with firebrick, the firebrick being set in mortar to retain said brick in position.

20 The life of these soaking-pit-covers has been very short due to the intense heat to which the covers are subjected, which causes a disintegration of the mortar and a loosening or falling out of the bricks.

25 The object of my invention is to provide a soaking-pit or furnace cover in which the bricks forming the lining are securely held in position, and practically form an integral part of the frame of the cover itself, thereby giving greater durability and greatly increasing the life of such soaking-pit cover.

To these ends my invention comprises the novel features hereinafter set forth and claimed.

35 In the accompanying drawing Figure 1 is a plan view of a mold, ready for pouring, to produce my improved soaking pit cover; Fig. 2 is a section on the line 2—2, Fig. 1; and Fig. 3 is a section on the line 3—3, Fig. 40 1 when the metal has been poured and the soaking pit cover completed and in position on the soaking pit.

The numeral 2 designates a bed of molding sand in which my improved furnace cover is cast. An ordinary wooden pattern is set down in the bed, the pattern conforming to the shape of the cover to be cast therein, and when said pattern is withdrawn, the mold cavity consists of the central square portion 3 with the radiating channels 4, and

adjacent the four corners the depressions 5 at the bottoms of which rest the core-pieces 6.

The refractory bricks 7 are laid on the level 8 of the mold cavity, said bricks being 55 laid in any suitable manner with reference to each other, but suitable spaces 9 being left between said bricks. Two layers of bricks are preferably employed, and the outer layer is laid to break joint with the 60 inner layer, as shown in dotted lines Fig. 1.

The mold is divided into four sections by the radiating channels 4, and in each section at or about the center thereof is the refractory circular tile 10 in which is inserted the 65 core 11.

When the mold has been made up in this manner, the molten iron or steel is poured into the mold cavity, and the said molten iron or steel rising in said cavity fills up all 70 the unoccupied spaces and rises up into the spaces 9 between the bricks so that when the mold is entirely filled, the bricks form an integral part of the entire casting and are 75 surrounded and incased by the metal.

When the metal is cooled and the pit cover is removed from the casting bed, the cores 6 and 11 having been removed, the pit-cover will have the appearance shown in Fig. 3 consisting of the inclosing body portion 12 80 with the ribs 13 radiating from the central hub portion 14, and with the lugs 15 at the corners to which are connected the bars 16 of the pusher for moving the pit-cover into and out of position over the soaking-pit 17.

By my invention, I provide a soaking-pit cover in which the brick lining may be formed of a double layer of bricks, the metal flowing in and around the bricks when the cover is cast, so as to make said bricks practically an integral part of the structure binding and tying them securely in place with the metal itself as distinguished from setting these bricks in mortar in the old manner of making these pit-covers, providing 90 thereby material which will resist the disintegrating action of the heat, and thereby greatly increasing the life of said covers.

What I claim is:

1. As a new article of manufacture, a fur- 100

nace cover or door formed of cast-metal with a brick lining, the metal forming the casting filling the spaces between said bricks and surrounding same.

5 2. In a new article of manufacture, a furnace cover or door formed of cast-metal with a plurality of layers of brick forming the lining, said brick being spaced apart,

and the metal forming the casting filling the spaces between said bricks.

In testimony whereof, I, the said JAMES D. ADAMS, have hereunto set my hand.

JAMES D. ADAMS.

Witnesses:

ROBT. D. TOTTEN,
JOHN F. WILL.
